UNITED STATES PATENT OFFICE.

FRANCIS W. PEARSON, OF BOSTON, AND ANDREW M. EASTMAN, OF SOMERVILLE, ASSIGNORS, BY DIRECT AND MESNE ASSIGNMENTS, TO ALBERT D. S. BELL, TRUSTEE, OF NEWTON, MASSACHUSETTS.

BURGLAR-ALARM.

SPECIFICATION forming part of Letters Patent No. 249,982, dated November 22, 1881.

Application filed July 13, 1881. (No model.)

To all whom it may concern:

Be it known that we, FRANCIS W. PEARSON and ANDREW M. EASTMAN, both citizens of the United States, residing, the former at 5 Boston, in the county of Suffolk and State of Massachusetts, and the latter at Somerville, in the county of Middlesex and State of Massachusetts, have jointly invented certain new and useful Improvements in Alarm-Bells and 10 Door-Knobs; and we do hereby declare that the same are fully described in the following specification and illustrated in the accompanying drawings.

This invention relates to improvements on 15 the patent granted to F. N. Cottle, March 25, 1879, No. 213,547, for alarm - bell and door-knobs; and it consists of an improvement in the striker mechanism of the hollow bell door-knob, the invention being carried out as follows, reference being had to the accompanying drawings, in which—

Figure 1 represents a longitudinal section of the device as applied to a door. Fig. 2 represents an end view of the interior mechanism 25 with the alarm-bell shown as removed; and Fig. 3 represents a cross-section on the line A B, shown in Fig. 1.

Similar letters refer to similar parts wherever they occur on the different parts of the 30 drawings.

a represents the door, with its lock *b*, outer knob or handle, *c*, and door - spindle *d*, in the usual manner.

e is the hollow shank of the knob *e'*, on the 35 inside of which the striker mechanism is located, as will hereinafter be described. The shank *e* is secured to the spindle *d* by means of the pin *f*, as shown in Figs. 1 and 3.

g is the hollow bell - knob, with its central 40 shank, *g'*, inserted into the central perforation of the hollow shank *e*, to which it is secured by means of the set-screw *h*, as shown in Fig. 1.

i is the knob-rose, secured to the inside of the door *a*, as shown, the central perforation 45 of which knob-rose serves as a bearing for the inner end of the hollow shank *e*. The knob-rose *i* is provided on its rim with a recess or opening, *i'*, bounded by cam - faces *i''* *i'''*, as

shown in Fig. 3. Within the recess *i'* is loosely resting the lower bent end, *k'*, of the lever *k*, as 50 shown in Fig. 1. The lever *k* has another bend, *k''*, in its upper end, projecting up through the duplex curved cam-groove *l'* in the laterally-adjustable latch-plate *l*, that is provided with a projecting lip, *l''*, that actuates a similar projection, *m'*, on the hammer-lever *m* when either of the knobs *c* or *g* is turned on their common axis to open the door, which hammer-lever is released from the latch-plate *l* before the door-lock is wholly withdrawn, when its 60 hammer *m''* is automatically caused to strike against the inside of the bell-knob *g* by the influence of the coiled spring *n*, attached in one end to the bent end *m'''* of said hammer-lever *m*, and in its other end to the screw *o*, secured 65 to the knob *e'*.

To properly guide the latch-plate *l* in its forward-and-back motion it is provided in one end with a straight slot, *p*, embracing the stationary guide-screw *p'*, secured to the knob *e'*, 70 and in its other end, nearest to the lip *l''*, with a curved cam-slot, *q*, embracing the stationary guide-screw *q'*, also secured to the knob *e'*, as shown in Fig. 2. As soon as either of the knobs *g* or *c* is released the latch-plate *l* is automatically moved to its normal position (shown 75 in Fig. 2) by the influence of the spring *r*, secured in one end to the set-screw *o*, and having its free end acting on the projection *s* on the latch-plate *l*, as shown in Fig. 2. By this arrangement the hammer *m''* is caused to strike against the inside of the bell - knob *g*, when either of the knobs *c* or *g* is turned previous to the complete release of the door-lock, producing a clear alarm when the outer knob, *c*, is 80 grasped, and a muffled sound by grasping the inner knob, *g*.

If it is desired to open the door without causing the hammer to strike, it is only necessary to slide the bent lever *k* toward the gong *g*, so 90 that the lower end, *k'*, of said lever is moved out of the recess *i'* on the knob-rose *i*, for which purpose said lower end, *k'*, may be provided with teeth or notches *t*, as shown in Fig. 1, or a projecting pin or equivalent device, as may 95 be desired. If it is desired to connect the

alarm, it is only necessary to slide the lower end, k' , of said lever into the recess i' to the position as shown in Fig. 1. By turning the spindle d , either by grasping the knob c or the knob g , the lever k raises the slotted latch-plate l p q , on account of its lower end, k' , resting in the slot i' in the knob-rose i , and when so turned its upper end, k'' , that projects through the duplex slot l' , causes the latch-plate l and its projection l'' to act on the lip m' on the hammer-lever m , and as the latch-plate l is guided toward the right by means of the guide q' and curved slot q , the projection l'' is made to pass by the lip m' on the hammer-lever m , releasing the latter and causing its hammer m'' to strike the inside of the gong g by the influence of the spring n . By releasing the grasp on either of the knobs c or g the latch-plate l is automatically moved to its normal position, as shown in Fig. 2, by the in-

fluence of the spring r , acting on the projection s .

Having thus fully described the nature, construction, and operation of the invention, we desire to secure by Letters Patent, and claim— 25

The herein-described improved alarm mechanism, consisting of the handles c and e' , shank e , spindle d , knob-rose i , its recess i' and cam-faces i'' i''' , bent lever k k' k'' , slotted latch-plate l p q , guides p' q' , projection l'' , cam-groove l' , the hammer m m' m'' , and springs n r , as and for the purpose set forth. 30

In testimony whereof we have affixed our signatures in presence of two witnesses.

FRANCIS W. PEARSON.
ANDREW M. EASTMAN.
